UNITED STATES PATENT OFFICE

FREDERICK U. CONARD, OF BRIDGEPORT, CONNECTICUT, ASSIGNOR TO UNDERWOOD
ELLIOTT FISHER COMPANY, OF NEW YORK, N. Y., A CORPORATION OF DELAWARE

PROCESS OF MAKING SPACING LEVERS FOR TYPEWRITING MACHINES

Application filed February 16, 1929. Serial No. 340,533.

This invention relates to improvements in process of making line-space levers for typewriting machines.

The levers may be formed by a cold proc-

ess of a single piece of metal, making them rugged, strong and durable. One of the advantages of this process lies in the fact that the levers can be made of metals not suscep-

10. not be heated to go through these operations.

Another advantage of the process for manu-

15. facturing the levers is the saving of metal used during this construction, so that the

scrap metal is a minimum. The levers are

also made of such a shape as to be easily fin-

ished by polishing and plating, or otherwise.

The levers have no joints, crevices or corners

20. to retain dirt as they would have if made

of several separate pieces assembled together.

25. In this invention the left-hand platen-

knob occupies the usual position with refer-

ence to the platen, but as this location is or-

30. dinarily occupied by the line-space lever in

portable machines, the lever in this case has

been bent upwardly and forwardly, forming

35. an offset in which space formed thereby the

knob may be located and where it is readily

accessible by the operator. The lever in plan

view may be substantially T-shaped, com-

40. posed of a longitudinal long arm and a lat-

eral short arm across the end of the long

arm. The short arm extends both sides of

the end of the long arm. One end of the short

45. lateral arm is pivoted to the carriage, while

the other end is pivoted to and actuates the

line-spacing mechanism of the platen. The

free end of the long arm is provided with

two integral lugs forming along with a pivot-

50. screw, in part, a bearing for a finger-piece

pivoted thereto and which is urged by a

spring towards a vertical position. The

finger-piece is constructed so that it may be

55. depressed.

Other features and advantages will herein-

60. after appear.

In the accompanying drawings,

Figure 1 is a perspective view of parts of

a typewriter, having this invention embodied

therein.

Figure 2 is a plan view of the spacing lever 50

after it has been blanked out of sheet-metal.

Figure 3 is a side view of Figure 2.

Figure 4 is a view of the lever shown in

Figures 1 and 2, after it has been twisted a

55. one-quarter turn.

Figure 5 is a view of the lever shown in

Figure 4, after it has been swedged in the

forming die.

Figure 6 is a transverse section through

Figure 5 and looking in the direction indi-

cated by the arrows 6—6.

Figure 7 is a side view of the lever shown

in Figure 5.

Figure 8 is a view of the lever after the raw

edges shown in Figure 5 have been trimmed.

65. The raw edges or fins are shown in dotted

lines.

Figure 9 is a side view of the lever shown

in Figure 8.

Figure 10 is a view of the lever after its 70

arm has been offset.

Figure 11 is a perspective view of the lever

in final form, ready to be assembled.

Figure 12 is a plan view of the assembled

parts, as shown in Figure 1, illustrating the

75. accessibility of the platen-knob.

Referring to the drawings, a platen 15 is

rotatably mounted on a platen-shaft (not

shown), journaled in the carriage 16 of the

typewriter. The platen 15 has an associated

80. ratchet-wheel 17 secured thereto, which is

rotated by a pawl 18, pivotally attached to a

slide-bar 19. The pawl 18 is normally dis-

engaged from the ratchet-wheel by a seat 50

secured to the frame of the carriage, so that

85. when the slide 19 moves backward taking the

pawl 18 with it, the latter drops into engage-

ment with the ratchet-teeth and rotates the

wheel 17 and consequently the platen 15 the

desired amount. A spring 20 is attached at

90.

one end to a screw 21, and the other end to the carriage, whereby the parts are returned to their initial position, as shown in Figure 1.

The slide-bar 19 is slidably mounted on the carriage 16, actuated by the lever 25, and has a lug 23, into which is threaded the screw 21. The latter has a shank which forms a pivot for the arm 24 on the lever 25. Another arm 26 on the lever 25 is pivoted on the shank of a screw 27, which is threaded into a pivot-block 28 that is attached to the end frame of the carriage. The arms 24 and 26, provided with bosses 29 and 30 having holes 39 and 40, respectively, are all integral with the lever-arm 31. The latter is offset at 32 and 33, Figure 10, to lie in an approximately parallel plane to that of the arms 24 and 26.

With reference to the process of making the lever 25 of one piece of metal, attention is called to the fact that heretofore it has not been possible to swedge side extensions forming lugs similar to 36 and 37 on a lever of this kind without using an excessive amount of metal; and even then it has only been possible to do so by a hot forging process. In this invention the lever 25 is made by a cold swedging process, as follows. The part that is to become a lever 25 is first punched out of sheet metal, as a blank, which may have a thickness somewhat less than the width of the finished lugs 36, 37. In the present embodiment of the invention the sheet metal is one-quarter of an inch thick, while the lugs 36 and 37 are five-sixteenths of an inch at the bottom and tapering off toward the top, as shown in Figure 11. This invention is, however, applicable for making levers of many sizes and shapes, and is not limited to any given dimensions. The blank 46, as shown in Figure 2, in this punching operation, is formed with a side projection or terminal 45, Figure 2; at one end thereof, which is, later on in the process, to form the lugs 36, 37. The blank is made with the short arms 24, 26 forming a terminal at the other end. The blank 46 is formed with the portion between the terminals having a slight lateral curve 47. The blank 46 may now be given a twist through ninety degrees between the terminals, as shown at 51 in Figure 4. The curve 47 in the long arm 31 is so formed in the blank 46 that when the blank is twisted, its lower side will lie approximately in a flat plane, see Figure 4. The twisted blank may now be placed in a suitable swedging die, and, under heavy pressure applied thereto, the metal of the blank is forced into all of the interstices of the die, see Figures 5 and 6. The surplus metal during the operation extrudes between the members of the die, as a fin 48, which, later on, may be trimmed to form the edges of the lever as desired, as in Figures 8 and 9. During the swedging operation the top of the lever is

arched by the die to give it greater rigidity, and, when finished, this arched top 34, Figure 5, presents a pleasing appearance. The lever may be given several swedging operations in the die to harden the metal and make the lever stiffer. The lug 35 on the end of the long arm 31, thus formed, may be milled across to form two lugs 36 and 37, which form, in part, the hinge for the finger-piece 43. Both lugs 36 and 37 are drilled, and one lug tapped to receive the screw 38, forming the pivot upon which the finger-piece 43 rocks. The finger-piece is provided with two ears 42. A spiral spring 44 on the pivot-screw 38 tends to retain the finger-piece 43 in its vertical position, shown in Figure 1. The spring 44 yields upon the cover of the case (not shown), being closed upon the finger-piece 43, making it rock downwardly under the cover.

Figure 11 illustrates the lever in its final shape, before being assembled with the finger-piece 43 and other parts, and before mounting in the carriage of the machine.

Figure 12 shows the relation of the platen-knob 49 to the lever 25, looking from the top. From this view it is seen that the long arm 31 of the lever 25 is mounted to the right of the knob 49, so that accessibility to the same is secured.

The finger-piece 43 is curved to form a finger-grip as shown in Figure 1.

To operate the lever disclosed herein for line-spacing, after the cover of the case has been removed and the finger-piece has assumed its vertical position, as shown in Figure 1, the finger of the operator engages the curved finger-piece 43 and presses it to the right. This swings the lever 25 on the pivot-screw 27 and moves the short arm 24 rearwardly. The latter moves the reciprocating slide-bar 19 with it, and also the pawl 18 pivoted thereto. During the first part of this motion the pawl 18 slides off the seat 50 and engages one of the teeth of the ratchet-wheel 17, moving the same through the desired letter-space distance. Continued pressure against the finger-piece 43 moves the carriage to the right of the machine, ready for typing another line. Upon removing the finger from the finger-piece 43, the lever 25 returns, by reason of the pull of the spring 20, to its initial position, taking the slide-bar 19 and the pawl 18 with it, until finally the pawl 18 again engages the seat 50, and is raised thereby out of engagement with the ratchet-wheel 17, thus permitting the free rotation of the platen in either direction by hand, if so desired.

Variations may be resorted to within the scope of the invention, and portions of the improvements may be used without others.

Having thus described my invention, I claim:

The herein-described process of making

levers for typewriting machines and the like, which consists in cutting a blank form from sheet metal, determined in form by the amount of metal required by the parts of the completed lever, then twisting the blank to properly distribute the metal, then applying pressure upon the twisted blank in a forming die to change it to the desired form, then trimming the edges according to the outline desired, and then bending the lever to form an offset-space for the platen-knob.
